UNITED STATES PATENT OFFICE.

HARRY E. SHELDON, OF PITTSBURGH, PENNSYLVANIA.

PROCESS OF TREATING METAL SHEETS OR PLATES.

1,016,715.

Specification of Letters Patent.

Patented Feb. 6, 1912.

Application filed March 21, 1905. Serial No. 251,297.

To all whom it may concern:

Be it known that I, HARRY E. SHELDON, a citizen of the United States, residing at Pittsburgh, in the county of Allegheny and State of Pennsylvania, have invented or discovered new and useful Improvements in Processes of Treating Metal Sheets or Plates, of which the following is a specification.

My invention relates to the process of treating metal sheets or plates whereby they are given a polished or Russia finish.

It is one of the objects of the present process to provide a continuous mill or process wherein all the steps are or may be carried on from the pickling operation in a continuous course automatically to the bluing and oiling operations.

My process contemplates the pickling of the metal, passing it through a scrubber or cleaning device, drying it, burnishing it on one or both sides, bluing, and oiling it.

The drawings accompanying the specification and forming a part hereof illustrate in Figure 1 diagrammatically in side elevation and vertical section one of the many individual mechanisms by which my process may be practiced, and in Fig. 2 a diagrammatic front elevation of the arrangement of the grinding and polishing device, which I prefer.

I will assume for the present that the process has to do with sheet steel after it has been placed in the usual pickling solution.

The sheets are placed in the pickling tank 1, and when sufficiently treated therein, are fed into the scrubber 2, which may be of any preferred construction, but is shown as having the feeding in pair of rolls 3, the feed out pair of rolls 4 and the intermediate pairs of rotary scrubbing rolls 5, composed preferably of wire brushes which rotate rapidly in contact with opposite sides of the sheets and clean them thoroughly. Water is supplied to the brushes during their operation by means of the pipes 6, or in any other selected manner.

The sheets pass from the scrubber 2 between several pairs of hollow drying rollers 7, heated internally by steam, flame, or otherwise.

The dried sheets pass from the drying rollers 7 to the grinding and polishing apparatus, indicated graphically by the pairs

of rolls 8 and 9, 10 and 11, 12 and 13, and 14 and 15. I have shown the rolls constructed to treat the upper surfaces only of the sheets, as the upper rolls 8 and 10 are shown to be composed of emery or other abradant, while all the lower rolls are made of soft yielding cloth disks strung and clamped together. The rolls 12 and 14 are composed of cloth disks or buffing material, soaked in emery or the like, though the roll 14 may in some cases not need to be supplied with an abradant. It is clear that the arrangement of the rolls might be reversed so that the lower surfaces of the sheets would be treated; or that the upper and lower rolls may alternately contain surface-treating material and sheet supporting material, two of each kind coöperating in pairs, so that both surfaces of the sheets would be treated. The sheets are passed back and forth between all the rolls and moved laterally at the same time, so that when they have passed beyond the rolls 14 and 15, they will carry a very highly polished surface or surfaces. The sheets may be carried back and forth through the rolls by any desired means, but I prefer that shown in the application of J. E. Lewis, filed March 8, 1905, and bearing Serial No. 249,048. I do not limit myself to the grinding or polishing devices described or referred to, but may make use of any means which will give the sheets a fine polished surface or surfaces.

From the buffer, the sheets pass to the bluing machine 10, which is preferably constructed in accordance with my application, Serial Number 245,583, or my application Serial Number 235,761.

I have shown the machine of my latter application. It consists of a pair of hollow rolls 16 and 17, which may be internally heated to redness by any suitable gas burner or otherwise. The roll 16 has parallel to it a series of small rollers 18 which guide the sheets from the table 19 between themselves and the roll 16 into the pass between the rolls 16 and 17. The sheets enter the said pass from the rear of the rolls; and as they issue from the same, they are stripped from the roll 17 by the stripper 20 and pass between the roll 17 and a series of rollers 21, which direct the sheets over the top of the roll 17 upon the table 22. The sheets, as they pass around the rolls 16 and 17 are

subject to several lines of pressure which travel from one end of each sheet to the other. At the same time they are subject to the heat transmitted from the rolls whereby they issue upon the table 22 with a glossy dark finish, known as a blue or Russia finish. Good results may be secured by the use of the rolls 16 and 17 alone, or by the omission of the rollers 21. By passing 10 around both rolls the treatment is prolonged and each side of the sheets is in contact with one of the rolls.

The sheets pass from the table 22 between the oiling rollers 23 and out upon the table 15 24, from which they are removed for storage or shipment, as desired. The oil is for the purpose of preserving the surface of the sheets.

Having described my invention, I claim—

The process of treating metals, which 26 consists in pickling the same, feeding them through a scrubber, and then drying them, smoothing and buffering the dried metal, and as a final step in the molecular distribution 25 of the metal subjecting it to a traveling line of pressure and simultaneously heating one surface as the line travels, and subjecting it to another traveling line of pressure and simultaneously heating the other surface as the line travels.

Signed at Pittsburgh, Pa., this 20th day of March, A. D. 1905.

HARRY E. SHELDON.
